CLAIM

The ornamental design for an animal feeder assembly, as shown and described.

DESCRIPTION

FIG. 1 is a perspective top front right view of an animal feeder assembly, comprising a base feature and a lid feature, showing my new design, wherein the perspective top rear left view is an identical image thereof;
FIG. 2 is a top plan view thereof;
FIG. 3 is a bottom plan view thereof; and,
FIG. 4 is a side elevation view thereof, wherein the remaining side elevation views are identical images thereof.
